VACUUM TUBE OSCILLATOR

Henry V. Neher, Arlington, Mass., assignor, by
mesne assignments, to the United States of
America as represented by the Secretary of War

Application January 13, 1944, Serial No. 518,135

5 Claims. (Cl. 315—5)

1

The invention described herein may be manufactured and used by or for the Government for governmental purposes, without the payment to me of any royalty thereon.

This invention relates to vacuum tube oscillators useful at frequencies of the order of 30,000 megacycles. As is well known, conventional vacuum tube structures with electrostatic grid control become inoperative at ultra high frequencies due principally to the transit time of electrons. In order to make such tubes operate, the electron path between cathode and anode may be designed in part or in whole as a resonant chamber or cavity for the frequency desired.

In a tube of the above character, the frequency generated is determined in a large measure by the constants of the resonant cavity, principally the geometrical configuration and dimensions. The variation of resonant frequency in the ultra high frequency region becomes quite considerable with variation in physical dimensions of the resonant cavity. Hence, with variations between tubes due to production inaccuracies and variations in circuits and systems with which a tube is supposed to cooperate, it is quite easy for one tube to be misaligned in the frequency spectrum. It becomes of great importance therefore to provide a tube structure which is susceptible to frequency tuning over a definite range.

This invention provides a tube structure having tuning means built in so that the resonant characteristics of the cavity resonator may be varied from outside the tube. The structure provided is simple, may be used in quantity production and results in a tube having highly desirable advantages.

In general, the invention provides a cavity resonator at least one wall of which is deformable. The deformation may be adjusted from outside the tube by suitable pressure on an elastic tube envelope or by heating current passed through suitable leads into the tube interior and acting on thermally responsive material cooperating with the deformable wall. Thus the fixed tuning of the cavity resonator may be adjusted within limits or the cavity may be continuously tuned over its tunable range to find a desired operating frequency.

Another determinant for proper tube operation is the potential gradient existing within various parts of the structure. The voltages necessary to establish desirable gradients are quite high. It follows therefore that the power supply for

2

such a tube must provide space current at a high voltage. It is quite important that generation of space current be efficient to eliminate waste of power. The invention hereinafter described provides an electron gun delivering practically all electrons emitted from the cathode surface as a fine beam travelling at a high velocity.

Referring now to the drawings, Figure 1 shows a sectional elevation along line 1—1 of Figure 3. Figure 2 shows a section along 2—2 of Figure 1. Figure 3 shows a section along 3—3 of Figure 1. Figure 4 shows a section along 4—4 of Figure 1. Figure 5 is an enlarged section of the high frequency output electrode and cable, and Figure 6 is an enlarged sectional perspective showing the resonant cavity and various control electrodes.

The vacuum tube is preferably formed of a generally cylindrical metal evacuated container 10 of the type on the market at present. Inasmuch as base connections are well known, no attempt is made to show them. Container 10 is made of any suitable metal usually iron and has disposed within it an annular frame 11, preferably of metal. Frame 11 may have any desired shape and as shown here consists of a bottom annular ring 12, a central section 13 cut away to save metal, and a top annular section 14 terminating in an annular flange 15. The entire tube structure may be supported by framework 11.

Snugly mounted within annular ring 12 is a heavy metal base plate 20. Base plate 20 may be locked to frame 11 prior to insertion within envelope 10 by means of one or more bolts 21 extending through annular ring 12 and into base plate 20. Base plate 20 may be made of any suitable metal preferably a relatively soft metal which may be fabricated easily. Thus base plate 20 may advantageously be fabricated from copper. As shown in Figure 1, base plate 20 has a relatively massive thickness and may have a plurality of apertures 22 and 23 through which leads may pass. In addition to these clearance apertures, base plate 20 may have a series—here shown as six—of apertures 24 to 29, inclusive.

As is clearly evident from Figure 3, base plate 20 is circular and the various apertures are symmetrically disposed. Base plate 20 is provided with two annular grooves or channels 30 and 31 on opposite faces thereof, groove 30 being on the bottom face while groove 31 is on the top face. The bottom face of base plate 20 has a center thereof cut away to form a generally cup

shaped recess 32, the center of which is cut out to form a generally conical chamber 33 passing through the entire base plate. Base plate 20 has the top face thereof cut away at the center to form a deep generally doughnut shaped chamber 34. As is clearly evident in Figure 1, conical chamber 33 extending up into doughnut shaped chamber 34 results in a generally hollow apertured cone 35 whose apex 36 is disposed a short distance below the plane of the top face of base plate 20.

Disposed against the bottom face of base plate 20 is an annular insulator 38 followed by an annular conductor 39 followed again by an annular insulator 40 thence by an annular conductor 41, thence again by an annular insulator 42 and finally by a relatively heavy end clamping plate 43. Similarly the top face of base plate 20 has alternate annular insulators 45, 47, and 49 interspersed with conductors 46, 48, and clamping plate 50. The entire structure is maintained rigidly together by a series of bolts here shown as three in number and disposed in apertures 25, 27, and 29. Inasmuch as these clamping bolts are metal and because of the high potentials impressed upon the various metallic members, it is preferred to cut away the clamp rings 43 and 50 and all the intervening metal members, the cutting away being around the bolts. These cut-aways, indicated by numerals 52 to 59, inclusive, provide a substantial surface path along the insulators and prevent breakdown.

To promote the ready assembly of the various parts, alternate apertures 24, 26, and 28 are provided, these apertures being adapted to fit accurately spaced rods in a jig over which the various members are threaded. Thus when the assembly is bolted, the jig may be removed without disturbing the alignment. In addition, these apertures provide gas dispersal paths during evacuation.

Annular metal member 39 carries a metal focusing cylinder 60 symmetrically disposed with respect to cup shaped recess 32. Symmetrically disposed within cylinder 60 is a generally cylindrical cup shaped cathode 61 extending well within cylinder 60. Cathode 61 has a flange 61' to which is spot welded three fingers 62 to 64, inclusive, extending downwardly from annular metallic member 41. Within cathode 61 there may be disposed a heating filament 66.

Referring to the top face of base plate 20, doughnut shaped chamber 34 is covered by a generally corrugated metallic diaphragm 68 of flexible material such as copper or steel. The peripheral portion of diaphragm 68 may be spot welded to the top face of base plate 20. Diaphragm 68 has a central aperture 69 collinear with conical aperture 36 and is adapted to cooperate with doughnut shaped cavity 34 to provide an adjustable resonant cavity. Above diaphragm 68 and insulated therefrom is metal member 46. This metal member is rigid and is provided with an aperture 70, collinear with apertures 36 and 69. Adjacent to aperture 70 are clearance apertures 71 and 72. Above metal member 46 is metal member 48 also rigid and having clearance apertures 73 and 74 in line with clearance apertures 71 and 72.

In order to control the position of diaphragm 68, a pair of posts 75 and 76 may be spot welded on opposite sides of central aperture 69. Posts 75 and 76 extend through clearance apertures 71 to 74, inclusive, as shown, and extend upwardly where the free ends are joined by a cross piece 77. Rigidly joined to cross piece 77 is a push rod 78.

the end of which is gripped by an insulating block 79. Carried by insulating block 79 is a conductor 80 carried by a lead 82. A tensioned heating wire 81 is welded to conductor 80 and the ends of wire 81 are spot welded to flange 15. Lead 82 may be used for supplying heating current to filament 81 when such current is desired. As wire 81 expands, bow spring 85 forces diaphragm 68 down.

Also fastened to rod 78 is a bowed spring 85 of the shape shown whose free ends 86 and 87 are spot welded to diametrically opposite points on flange 15. Disposed around the outside of envelope shell 10 is a rigid clamping ring 90 having a pair of clamping screws 91 and 92 disposed along the ring at an angle of 90° from each other. As shown in Figure 2, clamping ring 90 is somewhat larger in diameter than shell 10 and is rigid enough so that application of either screw 91 or 92 may distort the shell along the two diameters. It is clear that as shown in Figure 2 screw 92 tends to squeeze shell 10 so that the distance between ends 86 and 87 of the spring is increased. This tends to drop rod 78 and thus move flexible partition 68 down to reduce the volume of the cavity. By virtue of expansion induced by heating of filament 81 downward movement of rod 78 may be additionally provided.

For picking up oscillatory energy from cavity 34, a cable structure shown in Figures 3 and 5 is provided. As shown in Figure 3, base plate 20 is provided with a generally radial channel extending from cavity 34 outwardly through the tube structure. Spot welded to shell 10 is a cable structure comprising an outer metal sleeve 95 of any suitable shape and here shown as having a threaded end 96. Within sleeve 95 are two bores 97 and 98 separated by annular metal partition 99. Partition 99 has rigidly mounted therein a relatively fine metal tube 100 adapted to fit snugly within the channel formed in base plate 20. This metal tube 100 is adapted to extend through base plate 20 right into cavity 34. Within metal tube 100 is a quartz or glass tube 101 having a fine bore carrying a wire 102. The end of 102 is looped at 103 and connected to metal tube 100 at the end thereof so that a small loop is formed. This loop lies in a plane generally parallel to the length of the tube and functions as a pick-up electrode for ultra-high frequency energy. It is understood of course that the dimension of loop 103 together with the constants of the coaxial line and the resonant frequency of cavity 34 all cooperate to pick up oscillatory energy. Wire 102 is carried by a heavy metal rod 105 rigidly supported within sleeve 95 by suitable means such as a glass seal 106. Rod 105 together with sleeve 95 forms a coaxial cable and may be dimensioned to fit a standard coaxial coupling. It is understood of course that the entire coaxial assembly is sealed properly so that a vacuum within shell 10 may be maintained.

In practice, base plate 20 may be grounded. At a high negative potential thereto is cathode 61 while a still greater negative potential may be impressed upon cylinder 60 for the purpose of focusing electrons emitted from cathode 61. The electrons are emitted in the form of a pencil concentric with the axis of the structure and pass through aperture 36 as a fine beam. Due to the steep potential gradient existing between cathode 61 and base plate 20, the electrons are impelled at a high velocity to aperture 36. Between apertures 36 and 69 there is practically no static potential difference while beyond aperture 69 toward reflecting plate 48 the potential gradient

tends to slow down the electrons. Electrons reflected by reflector 48 may then be accurately focussed by back-focussing electrode 46, at cathode potential substantially, and thus pass back into cavity 34. Thus velocity modulation of the electron stream in such a manner as to bunch the electrons and cause oscillation at high frequency is brought about. Oscillations are picked up by loop 103 and conducted out.

The combination of cathode 61 and focussing cylinder 60 provides at conical aperture 36 a fine uniform stream of electrons moving at a substantially uniform velocity. The distance a from aperture 36 to aperture 69 is preferably small compared to the wave length of oscillations. In other words, the transit angle for distance a is small. Distance b from aperture 69 to reflector 48 is substantial in terms of wave length and transit angle. Roughly a proportion of about four to one for the ratio of b over a may be used.

It is essential that symmetry and rigidity be inherent in the structure. By virtue of the symmetry, quantity production may be obtained without serious impairment of quality. In particular the alignment and symmetry of the electrodes controlling the electron beam is important.

It is understood that leads to the various electrodes are provided and, with the exception of the coaxial cable, may run down to a standard tube base.

The tuning ring may be used for more or less fixed tuning over a substantial range. However some fine rapid tuning may be desirable and this may be obtained by applying a slowly varying current to heating wire 80. Thus an alternating current of about 10 cycles per second may be used to determine if the ring tuning is near the desired frequency. The filament tuning covers a small part of the tunable range and may be used not only for exploring but also for fixed accurate tuning. This may be accomplished by maintaining a direct heating current in filament 81.

What is claimed is:

1. A vacuum tube oscillator for use in ultra-high frequency comprising an evacuated metal envelope, said envelope containing the following elements mounted therein: a relatively massive block having flat faces on opposite sides thereof, and a generally doughnut shaped recess cut in one face thereof, said block having a channel therethrough along the axis of said recess, means on the other face of said block, for generating and focussing a beam of electrons on said axial channel and disposed along the axis, a flexible cover plate on said first face above said recess, said cover plate having the edge thereof rigidly secured to said block covering said recess and forming a cavity resonator, said cover plate being flexible along the axis of said cavity resonator to vary the volume thereof, a bowed spring disposed within said metal envelope, a mechanical connection from said spring to said flexible cover plate positioning said cover plate in accordance with the condition of said spring, means on the outside of said metal envelope and connected to said tensioning means for distorting the same to transmit force to said bowed spring for adjusting the resonant frequency of said cavity resonator, and a pick-up electrode passing through said envelope and block into said cavity.

2. A vacuum tube for use as an oscillator for ultra-high frequencies, said tube comprising a flexible metal envelope, said envelope being evacuated and supporting the following elements: a

massive metal block having flat faces on opposite sides thereof, one of said faces being cut away forming a generally doughnut shaped recess on one side, the other face being cut away forming a generally conical recess on the other side symmetrically disposed with respect to said first recess, a channel along the aligned axes of said tube recesses and passing through said block, means on the other side of said block, for generating and focussing a beam of electrons on said channel for passage through said block, a flexible metal cover plate disposed on said one face of said block covering said doughnut shaped recess to transform the same into a cavity resonator, said cover plate being rigidly and conductively secured to said block along the boundary of said recess, said cover plate having an aperture therethrough along the axis of said chamber through which the generated electron beam normally passes, a reflecting plate insulatingly carried by said block adjacent to and spaced from, said cover plate, a push rod fastened to said cover plate and passing through said reflector plate, a bowed spring anchored within said envelope to which said push rod is fastened, means encompassing said envelope for distorting said envelope to control said spring whereby the position of said cover plate is adjusted to control the volume of said cavity resonator, a pick-up electrode passing through said block and into said cavity for conducting oscillatory energy from said cavity resonator outside of said tube passing through said envelope for said electrodes.

3. The structure of claim 2 wherein an additional spring is anchored within said envelope, said additional spring being connected to said push rod and acting in opposition to said bowed spring and means connected to said additional spring adapted to be energized from outside said envelope for heating said additional spring to vary the tension thereof for controlling the movement of said cover plate.

4. A vacuum tube comprising an envelope of flexible metal, said envelope being evacuated and containing within it the following elements supported therein: a relatively massive block of metal having two flat faces on opposite sides, said block having a generally doughnut-shaped recess cut into one of said faces and a channel through said block axially of said recess, means on the other face of said block for generating and focusing a beam of electrons to pass along said axial channel, a flexible metal cover plate upon said recess to change the same to a cavity resonator, said cover plate being rigidly fastened to said block at the periphery of said plate, spring means anchored to said envelope and connected to said cover plate for biasing said flexible cover plate, said spring biasing means including a bowed spring disposed within said envelope and anchored thereto and connected to said cover plate, means connected to said spring biasing means adapted to be energized from outside said envelope for heating at least one part of said spring biasing means to vary the position of said cover plate and control the resonant frequency of said cavity resonator, and manually controlled means encompassing said envelope adapted to flex said envelope and change the position of said bowed spring whereby said frequency tuning may be accomplished either by said heating means or by said manually controlled means.

5. A vacuum tube for use as an ultra-high frequency oscillator comprising a flexible metal shell suitably evacuated and containing the following supported therein: a generally flat metal block

having a generally doughnut-shaped recess cut in one face thereof and a generally conical recess cut into the other face thereof and symmetrical with respect to said first recess, said block having a channel along the axis of said recesses and passing through said block, a cathode and focusing cylinder insulatingly mounted adjacent said other block face for directing a focused beam of electrons into said conical recess for passage through said channel, a flexible cover plate for said doughnut-shaped recess, said cover plate being rigidly fastened to said block around the boundary of said recess to form a cavity resonator, said cover plate having an aperture therethrough in line with said channel and being flexible along the axis of said channel, a back-focusing plate disposed adjacent said cover plate and having an aperture aligned with said channel, a reflecting plate disposed beyond said back-focusing plate, a push rod rigidly fastened to said cover plate and passing through clearance apertures in said back-focusing and reflecting plates, a bowed spring disposed between said push rod and said shell, said spring being anchored on the inside surfaces of said shell, and means adapted to be controlled from the outside of said shell for controlling the flexure of said spring to control the resonant frequency of said cavity

resonator, said last mentioned means comprising a clamp on the outside of said shell for distorting the same.
